(57) **CLAIM**

The ornamental design for a trailer mounted wet abrasive blasting unit, as shown and described.

DESCRIPTION

FIG. 1 is a perspective view of a trailer mounted wet abrasive blasting unit;

FIG. 2 is a top view of the trailer mounted wet abrasive blasting unit;

FIG. 3 is a right side view of the trailer mounted wet abrasive blasting unit;

FIG. 4 is a left side view of the trailer mounted wet abrasive blasting unit;

FIG. 5 is a front view of the trailer mounted wet abrasive blasting unit; and,

FIG. 6 is a rear view of the trailer mounted wet abrasive blasting unit.

Portions of the figures shown in broken, dashed lines illustrate the environment of the claimed ornamental features of the trailer mounted wet abrasive blasting unit and do not form any part of the ornamental design. Shading is shown in the figures merely to aid in the understanding of the scope of the claim.
